UNITED STATES PATENT OFFICE

2,430,417

GUIDE ROLLER

Leo G. Williams, Sr., Latrobe, Pa.

Application January 12, 1945, Serial No. 572,550

3 Claims. (Cl. 74—230.5)

1

This invention relates to a guide roller, and more particularly to such a roller adapted to serve as a guide for coiling hot or cold springs, casings, tubes, or the like about a mandrel.

A primary object of this invention is the provision of an improved roller serving to supplant the guides customarily used in such operations, and adapted to provide a suitable guide die in itself for coil springs of a variety of sizes, within the limits of the device.

Still another object of the invention is the provision of such a guide roller provided with means whereby the same may be readily adapted to take either round or square stock.

A still further object of the invention is the provision of such a device provided with means whereby in the event the guide roller becomes worn portions thereof may be replaced readily and with a minimum of difficulty, without the necessity of replacing the entire guide roller.

Other objects reside in the provision of a device of this character which will be sturdy and durable in construction, reliable and efficient in operation, and relatively simple and inexpensive to manufacture.

Still other objects reside in the combinations of elements, arrangements of parts, and features of construction, all as will be more fully pointed out hereinafter and disclosed in the accompanying drawings, wherein there is shown a preferred embodiment of this inventive concept.

In the drawings:

Figure 1 is a side view partially in section and partially in elevation showing the roller of the instant invention in association with a piece of stock adapted to be wound in helical form about a mandrel.

Figure 2 is a top plan view of the roller shown in Figure 1.

Figure 3 is an enlarged sectional view taken substantially along the line 3—3 of Figure 2, as viewed in the direction indicated by the arrows.

Figure 4 is a side elevational view of an element of construction.

Figure 5 is a view similar to Figure 2 but showing the parts in a different position of adjustment, certain additional parts being added, and

Figure 6 is a sectional view taken substantially along the longitudinal center line of Figure 5.

Similar reference characters refer to similar parts throughout the several views of the drawings.

Having reference now to the drawings and more particularly to Figure 1, there is generally indicated at 10 a base of any desired configura-

2

tion, to which is secured a support 11, carrying a rotatable mandrel 12, about which is adapted to be wound stock 13, in helical form. The mandrel 12 may be rotated in any desired conventional manner.

The guide roller, generally indicated at 14, of the instant invention is adapted to be mounted on a base plate 15, as by means of a protruding post or bar 16. The bar 16 terminates in a circular flange member 17, having a horizontally disposed central bore 18 therethrough.

The bore 18 is adapted to have passed therethrough a threaded portion 19 of a relatively heavy bolt 20, terminating in a head 21 having a slot 22 therein. Surrounding the shank of the bolt 20 is a collar 23, provided with a peripheral flange 24 at its end the interior of which is arcuately curved as at 25 to form a bevel edge. A countersunk depression 21' is adapted to accommodate the head 21 of the bolt 20.

The sleeve 23 is rotatable upon bolts 20 and is adapted to be surrounded by a second sleeve 26 the interior diameter of which is slightly in excess of the external diameter of the sleeve 23, 25 and the interior face of which terminates in an arcuate peripheral portion 27 terminating in a feather edge 28 adapted to coat with the arcuate portion 25 to provide a groove or channel of semi-circular configuration.

30 The outer extremity of the shank of the bolt 19 is adapted to be engaged by an internally threaded nut 30.

The portion of the sleeve 26 normally adapted to abut the face of the member 17 is substantially flat as indicated at 31.

Now from the foregoing it will be seen that the groove formed by the members 25 and 27 forms a channel for a piece of stock of circular cross-sectional configuration, the size of which may be 40 readily varied in accordance with the positioning of the nut 30 on the bolt 19. Obviously, the same roller may be utilized for a variety of sizes of dies as desired.

Under certain conditions, as for example when 45 it is desirable to roll square stock into a coil spring, the device of the instant invention may be equally advantageously utilized. Under such conditions the nut 30 is removed from the bolt 19 and the sleeve 26 removed from the sleeve 23. A washer 35 is then positioned adjacent the arcuate extremity 25 of the flange 24, and the sleeve 26 repositioned thereon, but with the flat edge 31 in facing relation with the flat edge of the washer 35. The feather edge 28 is then reversely positioned toward the member 17. A second washer

36 is positioned on the shank, to protect the feather edge 28 and the shank 19 of the bolt 20 is passed through the aperture of the member 17 and the nut 30 rethreaded thereon.

Thus under these circumstances the square stock passes between the face 31 and the inner face of the washer 35, to provide a channel, rectangular in cross section, adapted to accommodate the stock.

Obviously, the positioning of the nut 30 will determine the width of the channel between the washer 35 and the face 31 in order to determine the size of the stock which may be advantageously accommodated.

From the foregoing it will now be seen that there is herein provided a device which accomplishes all the objects of this invention and others including many advantages of great practical utility and commercial importance.

It will also be seen that the device of the instant invention provides a single roller adapted to supplement and normally to supplant the previous variety of sizes, shapes and conditions of dies utilized to accommodate various types of stock.

I claim:

1. In a guide roller, in combination, a support, a bolt passed through said support, a cylindrical sleeve surrounding said bolt, a flange on said sleeve having an arcuately tapered inner face, a second cylindrical sleeve coaxially surrounding said first-mentioned sleeve and journaled thereon and having a feather edge coacting with said inner face to form a channel of semi-circular cross-sectional configuration, said second sleeve having a substantially flat perpendicular outer face and being reversible with respect to said first sleeve to provide a groove therebetween having a vertical, flat guide wall.

2. A guide roller comprising a cylindrical sleeve having a peripheral flange at its outer end merging into the sleeve, a second cylindrical sleeve of the same diameter as the peripheral flange, coaxial with and journaled upon the first sleeve and having an end surface curving downwardly and outwardly into a feather edge, said two sleeves cooperating to provide a semi-circular groove between the flange and the end surface, and nut and bolt means comprising a journal means and a retaining means for said sleeves.

3. A guide roller comprising a cylindrical sleeve having a peripheral flange at its outer end merging into the sleeve, a second cylindrical sleeve of the same diameter as the flange, having a flat, vertical end surface on one extremity and a feather edge merging into the end surface of the other extremity, said second sleeve being journaled solely upon said first sleeve in selective reversible position, said flange at the end surfaces of said second sleeve being selectively positioned in juxtaposition to constitute a guide groove having a semi-circular cross-section or a guide groove with a vertical end wall.
